UNITED STATES PATENT OFFICE.

MARTIN T. CHAMBERLAIN, OF JOLIET, ILLINOIS.

WALL CLIP.

Application filed March 10, 1928. Serial No. 280,651.

My present invention relates to improvements in wall clips designed especially for use in connection with fibrous slabs for the purpose of fastening them together at their 5 joints.

The wall clips are designed to extend transversely through the slab or wall, or partition, and the opposite ends of the clip are designed to be partly or wholly embedded in the fibrous slabs and then covered by plaster or other wall covering that is applied in usual manner to the faces of the walls formed over the clamped slabs.

The primary object of the invention is 15 the provision of an inexpensive but highly efficient device of this character which is applicable for use with various thicknesses and shapes of slabs, and which will insure a firm grip upon the opposite faces of the 20 walls of partitions formed by the use of the slabs.

The invention consists in certain novel combinations and arrangements of parts as will hereinafter be more fully set forth and 25 claimed. In the accompanying drawings I have illustrated one complete example of the physical embodiment of my invention together with two slight modifications thereof in which the parts are combined and arranged 30 according to the best modes I have so far devised for the practical application of the principles of my invention.

It will be understood that various changes and alterations may be made in the exemplified structures within the scope of my claims 35 without departing from the principles of my invention.

Figure 1 is a face view showing a pair of adjoining fibrous slabs clamped together by 40 one of the clips of my invention.

Fig. 2 is a sectional detail view of the device of Fig. 1.

Fig. 3 is a sectional detail view of a modified form of the invention.

Fig. 4 is a perspective view showing a wall clip adapted to a wall and partition structure.

In Fig. 1 the two abutting slabs A and B are indicated as fashioned of fibrous material which is to some extent pliable and the surface of these slabs may be penetrated by the clamping plate 1 to secure the wall clip in rigid position. The clamping plates 1 are used in pairs as indicated and while they 50 are shown in circular form it will be apparent that other shapes may be used if desired.

In order to reduce weight of the plates and to provide anchoring means for the plaster or wall covering applied to the faces of the slabs, the clamp plates are perforated as at 60 2. At the center of the plate a center hole 3 is provided and at the periphery of the plate an annular flange 4 which is slightly turned in is fashioned so that when the plate is clamped against the face of the fibrous 65 wall this flange will penetrate or embed itself in the face of the slabs in addition to the central portion of the clamp plates. In this manner the opposing plates at opposite sides of the wall or partition structure are 70 rigidly secured in the faces of wall or partition. In combination with the clamp plates I use a pair of cupped clamp disks 5 fashioned of metal, as are also the clamp plates fashioned of metal, and this cupped 75 disk has a countersunk center 6 in which a bolt hole 7 is provided. These cupped disks are used in pairs with the clamp plates and they are seated in the center holes 3 of the 80 plates and connected by a tie bolt or other fastening means as 8. The bolt is fashioned with a head 9 located in the countersunk or cupped disk 5 and on the threaded end of the bolt a nut 10 is located in the countersunk or cupped disk at the opposite side of the 85 wall. Thus it will be apparent that when the bolt 8 is passed through the joint between the slabs A and B with the clamp plates and clamp disks put in proper place, then by turning nut 10 the opposing clamp 90 plates are firmly gripped into and partially or wholly embedded in the opposite faces of the slabs A and B to provide a firm and secure joint.

In Fig. 3 the modified form of the device 95 is shown wherein a pair of concavo-convex clamp plates 11 are used on the tie bolt 8, and these plates are fashioned with the anchoring perforations 12. At their centers these concavo-convex clamp plates are countersunk as at 13 and provided with bolt holes 14 in order to accommodate the clamp bolts 8 and their respective heads and nuts 9 and 10. The same effect as the annular flanges 4 in Figs. 1 and 2 is secured by the 105 use of concavo-convex clamp plates 11 in Fig. 3, and the annular edges together with the central portion of these clamp plates are embedded in the faces of the fibrous slabs. Should the plates be placed against the faces 110 having irregularities in them, it will be apparent that as the nut 10 is turned home the

opposing plates will be caused to uniformly penetrate the opposite faces of the structure and thus compensate for the irregularities. Should the slabs vary slightly in thickness 5 these variations also may be compensated for by drawing the plates toward each other with the tie bolt. In Fig. 4 I have indicated by dotted lines a wall structure C and a partition structure D disposed at right 10 angles, and these structures are jointed by wall clips fashioned from integral angle plates 15 and 16 that are provided with the anchoring perforations 2 and also with the cupped disks 5 and tie bolts 9 and with the 15 nuts 10. It will be apparent that the angle clamps will be used in pairs, and with this pair of angle clamps another pair of clamp plates are used, or a single clamp plate may be used in lieu of the latter pair of plates. 20 By the utilization of the wall clips of my invention, thin partitions may be erected in building structures and the partitions are provided with the desired rigidity, sound-proofing and of extremely light weight. The 25 partitions or walls made from the fibrous slabs may be laid with rapidity and it will be apparent that the wall clips take the place of mortar in the joint. The sections or slabs thus incorporated in the partition or wall 30 may be trued and alined with facility preparatory to adding the plaster or face covering to the walls or partitions, and a minimum amount of labor and time are required for laying up the wall or partition having 35 the wall clips embedded therein.

The wall clips may be used to clamp a plurality of fibrous slabs at their meeting

points and as illustrated in the drawings slabs forming walls or partitions in different planes may also be joined.

40

The clamp plates, it will be apparent, may be fashioned in an inexpensive manner and they may be made from scrap pieces of material without the necessity for use of expensive or costly stamping machines. The 45 wall clamps readily adapt themselves to the edges of the slabs and should the edge of one slab be adjoined by the edge of a thinner slab, or say four slabs meet at their corners each with a slight difference in thickness, it will be apparent that the clamp plates will uniformly penetrate and embed themselves in the irregular faces of the slabs to make a solid connection.

50

The slabs as indicated are laid on edge and 55 the joints of the courses or tiers may be staggered so that the wall clips will engage three different slabs, thus insuring a strong and durable wall structure.

55

Having thus fully described my invention, 60 what I claim is new and desire to secure by Letters Patent is:

65

A wall clip comprising a pair of spaced perforated clamp plates having inturned annular flanges and an open center, a cupped 70 disk having a bolt hole and located in each of the open centers, and a tie bolt connecting said cupped disks and provided with a head and nut on its respective ends whereby a spring action is obtained when the annular flanges bite into the slab.

70

In testimony whereof I affix my signature.

MARTIN T. CHAMBERLAIN.
